DESIGN FOR AN ASH RECEPTACLE

Fred Rees, Meriden, Conn.

Application November 7, 1933, Serial No. 49,668

Term of patent 7 years

To all whom it may concern:

Be it known that I, FRED REES, a citizen of the United States, residing at Meriden, in the county of New Haven and State of Connecticut, have invented a new, original, and ornamental Design for an Ash Receptacle, of which the following is a specification, reference being had to the accompanying drawing, forming part thereof.

Figure 1 is a perspective view of the ash receptacle showing my new design.

Fig. 2 is a front elevation of the same.

Fig. 3 is a side view of the same.

I claim:

The ornamental design for an ash receptacle, as shown.

FRED REES.
